UNITED STATES PATENT OFFICE

JOHN H. FLINK, OF WATERTOWN, MASSACHUSETTS, ASSIGNEE, BY MESNE ASSIGNMENTS, TO HOOD RUBBER COMPANY INC., OF WATERTOWN, MASSACHUSETTS, A CORPORATION OF DELAWARE

BOOT-TREE

Application filed December 3, 1928. Serial No. 323,299.

This invention relates to improvements in boot trees or lasts of the type employed in the manufacture of rubber boots, and in which the lasts are preferably constructed of metal and have a toe section which is separable from the leg section to facilitate the removal of the last from the completed boot.

The object of the invention is to provide a boot tree or last of the type mentioned, of strong and durable construction, the toe section having a guide member rigidly secured thereto which is slidable within another guide member which is pivotally mounted upon the leg section, and a simple and efficient means being provided upon the pivoted guide member for interlocking with the slideable guide member and thereby holding the toe and leg sections in abutting relation.

Another object of the invention is to so position the slideable and pivoted guide members that in moving the toe section of the last upon the leg section thereof that the longitudinal abutting faces of the toe and leg sections will slide one upon the other and a tongue provided upon the toe section will be guided between ways formed upon the leg section.

Still another object of the invention is to provide a means for forcing the abutting faces of the toe and leg sections tightly together when said sections are located in their normal or locked position.

The invention consists in a boot tree or last as set forth in the following specification and particularly as pointed out in the claims thereof.

Referring to the drawings:

Figure 1 represents a side elevation of a boot tree embodying my invention, the leg section being broken away to save space in the drawings and the toe and leg sections being shown in their normal or locked position.

Fig. 2 is a sectional elevation of the lower portion of the boot tree, the toe section being shown in its extreme open position.

Fig. 3 is a detail section taken on the line 3—3 of Fig. 1.

Like numerals refer to like parts throughout the several views of the drawings.

In the drawings, 5 represents a main or leg section of a boot tree or last and 6 represents a toe section, said sections having oppositely disposed abutting faces disposed in intersecting planes as indicated at A and B, the plane A being substantially lengthwise of the leg portion and the plane B being substantially perpendicular thereto. The leg and toe sections are preferably hollow and constructed of aluminum.

Pivotedly mounted on a pin 7, which is located at the lower end of the leg section 5, is a guide member 8 having a dove-tail shaped groove 9 formed therein. A guide member 10, rigidly secured to the toe section 6, is slidably mounted in the groove 9. The guide members 8 and 10 are so positioned upon the leg and toe sections respectively of the last that when said sections are located in their normal or closed position that a rear face 11 of the toe section will abut against a front face 12 of the leg section in the plane A. A tongue 13, furthermore, projects rearwardly a short distance from the face 11 of the toe section 6 between ways 14 provided upon the leg section 5 and when the toe section is moved upon the leg section, this latter guiding means co-operates with the guide members 8 and 10 in guiding the movement of the toe section upon the leg section.

As it is desirable that there shall be some clearance between the guide members while the toe section is being moved upon the leg section, and as it is also desirable that the looseness caused by the clearance shall be eliminated when the sections are locked together, a means is provided for forcing the opposite abutting faces of the toe and leg sections together when said sections are in their normal or closed position. This mechanism is as follows:—Located at the front of the upper portion of the guide member 10 is a surface 15 which is bevelled slightly relatively to the front face of said guide member and during the upward movement of the toe section 6, this bevel face engages a roller 16 which is rotatably mounted upon a pin 17 in turn mounted in the leg section 5. The action of the roller 16 is to force the guide member 10 and toe section 6 rearwardly as

said members reach their uppermost position upon the leg section 5, and when the toe section reaches the extreme limit of its upward movement, the pressure of the roller 16 upon the front face of the guide member 10 will 5 force the adjacent abutting faces 11 and 12 of the toe section 6 and leg section 5 respectively tightly against each other.

A pin 18 mounted adjacent to the top of the 10 guide member 10 projects from the opposite sides of said guide member and contacts with the upper surface of the guide member 8 and thereby limits the downward movement of the member 10 upon the member 8.

Means are provided for locking the toe and 15 leg sections in their normal or closed positions as follows:—Located in the rear surface of the guide member 10 is a recess 19 and mounted in a recess 20 provided in the guide 20 member 8 is a spherical member 21 which is forced by a spring 22 into contact with the rear surface of the guide member 10. When the toe section is located in its uppermost position upon the leg section 5 and the adjacent faces of said sections are contacting 25 one with the other, the spring 22 will force the spherical member 21 into the recess 19 which, at this time, is located in alignment with the member 21 and the toe and leg sections will be locked together.

When it is desired to remove the last from the boot an eye member 23 at the top of the leg section 5 of the last is attached to a hook, and a pull upon the leg portion of the boot 35 causes the leg section of the last to move out of the boot leaving the toe section 6 of the last in the toe portion of the boot until the oppositely disposed faces of the toe and leg sections are disengaged from each other, 40 whereupon the toe section 6 will swing rearwardly out of the toe portion of the boot, said toe section rocking upon the pivot 7 into the position illustrated in Fig. 2, thereby permitting the entire last to be withdrawn 45 through the leg portion of the boot.

I claim:

1. A boot tree or last comprising, in combination, a leg section and a toe section separable from each other, a guide member pivotally mounted on said leg section, and another guide member fast to said toe section and slidable upon said pivoted guide member.

2. A boot tree or last comprising, in combination, a leg section and a toe section separable from each other, a guide member pivotally mounted on said leg section, another guide member fast to said toe section and slidable upon said pivoted guide member, and 60 means to lock the toe and leg sections together.

3. A boot tree or last comprising, in combination, a leg section and a toe section normally abutting together and also separable 65 from each other, a guide member pivotally

mounted upon said leg section, another guide member fast to said toe section and slidable upon said pivoted guide member, and means to hold the toe and leg sections in abutting relation.

4. A boot tree or last comprising, in combination, a leg section and a toe section provided with oppositely disposed abutting faces, a guide member pivotally mounted upon said leg section, and another guide member fast to said toe section and slidable upon said pivoted guide member, said toe section being separable from said leg section at said faces and being adapted to swing, when separated, in unison with the pivoted guide member upon the leg section.

5. A boot tree or last comprising, in combination, a leg section and a toe section provided with oppositely disposed abutting faces, a guide member pivotally mounted upon said leg section, another guide member fast to said toe section and slidable upon said pivoted guide member, said toe section being separable from said leg section at said faces and being adapted to swing, when separated, in unison with the pivoted guide member upon the leg section, and means to hold the toe and leg sections in abutting relation.

6. A boot tree or last comprising, in combination, a leg section and a toe section provided with oppositely disposed abutting faces, a guide member pivotally mounted upon said leg section, another guide member fast to said toe section and slidable upon said pivoted guide member, said toe section being separable from said leg section at said faces and being adapted to swing, when separated, in unison with the pivoted guide member upon the leg section, and means upon said pivoted guide member to interlock with said slidable guide member and hold the toe and leg sections in abutting relation.

7. A boot tree or last comprising, in combination, a leg section and a toe section provided with oppositely disposed abutting faces, a guide member pivotally mounted upon said leg section, another guide member fast to said toe section and slidable upon said pivoted guide member, said toe section being separable from said leg section at said faces and being adapted to swing, when separated, in unison with the pivoted guide member upon the leg section, and a spherical member yieldingly mounted in the pivoted guide member and adapted to interlock with a recess in the slidable guide member, whereby the toe and leg sections are held in abutting relation.

8. A boot tree or last comprising, in combination, a leg section and a toe section normally abutting together and also separable from each other, co-operating guideways upon said toe and leg sections permitting a sliding movement therebetween, a guide member pivotally mounted upon the leg sec-

tion, another guide member fast to the toe section and slideable upon said pivoted guide member, and means to hold the toe and leg sections in abutting relation.

5 9. A boot tree or last comprising, in combination, a leg section and a toe section provided with oppositely disposed abutting faces, co-operating guideways upon said toe and leg sections permitting a sliding movement between said opposite faces, a guide member pivotally mounted upon the leg section, another guide member fast to the toe section and slideable upon said pivoted guide member, the toe section being separable from the leg section at said faces and being adapted to swing, when separated, in unison with the pivoted guide member upon the leg section, and means to hold the toe and leg sections in abutting relation.

20 10. A boot tree or last comprising, in combination, a leg section and a toe section provided with oppositely disposed abutting faces, a guide member pivotally mounted upon said leg section, another guide member fast to said toe section and slideable upon said pivoted guide member, the toe section being separable from the leg section at said faces and being adapted to swing, when separated, in unison with the pivoted guide member upon the leg section, and means upon the leg section to engage the slideable guide member during its closing movement and force the opposite faces of the leg and toe sections tightly together.

35 11. A boot tree or last comprising, in combination, a leg section and a toe section provided with oppositely disposed abutting faces, a guide member pivotally mounted upon said leg section, another guide member fast to said toe section and slideable upon said pivoted guide member, the toe section being separable from the leg section at said faces and being adapted to swing, when separated, in unison with the pivoted guide member upon the leg section, and a roller mounted upon the leg section and engaging the slideable guide member during its closing movement to force the opposite faces of the leg and toe sections tightly together.

50 12. A boot tree or last comprising, in combination, a leg section and a toe section provided with oppositely disposed abutting faces, co-operating guideways upon said toe and leg sections permitting a sliding movement between said opposite faces, a guide member pivotally mounted upon the leg section, another guide member fast to the toe section and slideable upon said pivoted guide member, the toe section being separable from the leg section at said faces and being adapted to swing, when separated, in unison with the pivoted guide member upon the leg section, means to force the opposite faces of the toe and leg sections tightly together, and

means to hold the toe and leg sections in abutting relation.

In testimony whereof I have hereunto set my hand.

JOHN H. FLINK.
